UNITED STATES PATENT OFFICE

PAUL B. RENFREW, OF FORT WAYNE, INDIANA, ASSIGNOR TO S. F. BOWSER & COMPANY, INC., OF FORT WAYNE, INDIANA, A CORPORATION OF INDIANA

DESIGN FOR A DISPENSING CASING

Application filed January 22, 1930. Serial No. 34,226. Term of patent 14 years.

To all whom it may concern:

Be it known that I, PAUL B. RENFREW, a citizen of the United States, residing at Fort Wayne, in the county of Allen and State of Indiana, have invented a new, original, and ornamental Design for a Dispensing Casing, of which the following is a specification, reference being made to the accompanying drawing, forming a part thereof.

In the drawing—

Fig. 1 is an elevational view of one side of a dispensing casing embodying my new design; and

Fig. 2 is an elevational view of the opposite side thereof.

I claim:

The ornamental design for a dispensing casing, as shown.

Fort Wayne, Indiana, January 19, 1930.

PAUL B. RENFREW.
